UNITED STATES PATENT OFFICE.

FRANK L. O. WADSWORTH, OF PITTSBURGH, PENNSYLVANIA.

WATER-HEATER CONSTRUCTION.

1,243,017.

Specification of Letters Patent. Patented Oct. 16, 1917.

Application filed February 19, 1916. Serial No. 79,307.

To all whom it may concern:

Be it known that I, FRANK L. O. WADSWORTH, a citizen of the United States, residing at Pittsburgh, in the county of Allegheny and State of Pennsylvania, have invented certain new and useful Improvements in Water-Heater Constructions, of which the following is a specification.

My invention relates to improvements in water heater construction and has for its object the provision of an actuating mechanism for the fuel supply valve which becomes operative only when the heater coils or receptacle is being supplied with water, and which when so rendered operative, is under the direct and sole control of thermostat element immersed in the water being heated. In the mechanism I use the movements of a water actuated member not to directly affect the opening or closing of the fuel valve but only to bring the thermostatically actuated parts into operative relationship with the fuel valve parts so that said valve will be closed when the temperature rises above this point. As shown in the various figures of the drawings which form a part of this specification the principle of control above described may be carried out by various forms of mechanism, all of which are simple, easily constructed and mechanically reliable.

In the accompanying drawings which show certain illustrative embodiments of the invention—

Figures 1 and 2 are respectively a front and side elevation of one of the ordinary forms of multiple coil instantaneous water heaters with my improvement applied thereto; Fig. 3 is a central section on an enlarged scale through the form of control mechanism which is shown in Figs. 1 and 2; and Figs. 4, 5 and 6 are similar views of modified forms of control applicable to the same or different forms of hot water heaters.

Referring first to the general arrangement of the heater parts as shown in Figs. 1 and 2, A is the casing of the heater; B and C are the upper coils of the heater; D is the lower reverse coil connected to the upper coils by means of the pipe E; F are the burners mounted upon the usual burner ring; G is the gas supply pipe; H is the casing of the gas valve for controlling the supply of gas to the burners; I is a pipe leading from the gas valve to the burner

ring; and K is the casing of the water pressure controlled member.

Referring to Fig. 3 in connection with Figs. 1 and 2; 1 indicates the cold water pipe leading from the water main to the piston chamber 2 containing the water actuated member of the control mechanism, and 3 indicates the pipe leading from said piston chamber to the upper end of the heater coils B. After passing through these coils and the lower connected coils C and D the water emerges from the out-let 4 and enters the lower end of a thermostat chamber 5, and flows upward therethrough to the out-let pipe 6 connected with the house supply system. The piston chamber 2 contains a liquid actuated piston member 7 which is of the central discharge "bungalow" type. The central conical bore of this piston engages—when the piston is in its lower or closed position—with a conical plug 8, which is seated in a projecting boss 9 on the lower head of the piston chamber 2, and is pressed upwardly into engagement with the conical bore of the piston 7 by means of the spring 10. The stem 11 is secured at its upper end to the central hub of the piston 7, passes down through a stuffing box 12 in the cap covering the end of the boss 9, and carries at its lower end an adjustable thumb nut 13 which is adapted to engage with a lever 14. The said lever 14 is pivoted at 15, and is held down by a spring 16 attached to its outer end, the tension of this spring being adjustably controlled by the screw 17. The thermostat chamber 5 contains a composite copper-iron, or copper-porcelain thermostat element of the usual construction, the positive copper element 18 being secured in its lower end to the adjacent portion of the thermostat chamber 5, and the negative iron or porcelain element 19 being secured in its upper end to the positive element 18 and provided at its lower end with an adjustable knife edge or pivot point 20 which is adapted to engage with the short arm of a thermostat lever 21. This thermostat lever is mounted on a double pivot point support 22 (one of these pivot points being in front and the other to the rear of the plane of the drawings) which is fixed not to the frame of the mechanism as in the usual construction, but to a pivoted member 23 which is provided with a knife edge 24 bearing on the lever 14, the normal position of the

members being such that when the said lever 14 is in its lowest position the thermostat lever 21 is entirely out of engagement with the knife edge or pivot point 20. The thermostat lever 21 is perforated for the free passage of the valve stem 11, and engages at its outer end with an adjustable thumb nut 25 on the stem 26 of the gas valve 27. This gas valve is normally held against its seat both by the pressure of its own spring 28 and also by the pressure of the spring 16 which acts upon the stem 26 through the medium of adjustable collars 29 engaging with the lower face of the lever 14. When this gas valve is against its seat all flow of fuel from the gas supply pipe G to the gas delivery pipe I is cut off; and in the position of parts shown in Fig. 3 it is obvious that no movement of the gas valve 27 can be effected by the expansion or contraction of the thermostat parts 18 and 19.

The operation of the above described device is as follows: When a flow of water is started through the heater by opening a tap in the house supply pipe 6, the pressure on the upper side of the piston 7 is reduced, and the pressure of the water in the supply pipe 1, and in the lower part of the piston chamber communicating therewith, lifts the piston 7 away from the conical valve plug 8 and allows the water to flow through the central piston opening to the water inlet pipe 3 of the heater coils. The form of the valve plug 8 is such that a very considerable upward movement of the piston 7 is necessary to establish the required opening for the delivery of the required amount of water to the heater coils, even when the heater is only delivering its minimum supply of water. This upward movement of the piston 7 lifts the valve stem 11, and with it the lever 14 until the outer end of the said lever is brought into engagement with an adjustable screw stop 30, which limits and determines both the upward movement of the lever and of the water actuated member 7. The lifting of this lever relieves the gas valve stem 26 from the pressure of the spring 16, but the gas valve still remains closed under the pressure of its own spring 28, until it is acted upon independently by the thermostatically controlled parts. These parts are brought into operative engagement with the valve parts by the raising of the pivoted member 23, and with it the thermostat lever 21 until the latter is brought against the knife edge or pivot point 20 of the thermostat member 19. As soon as this occurs the gas valve is brought under the control of the thermostat and remains under its control as long as the lever 14 is held in its elevated position by the flow of water through the heater. If the temperature of the flowing water is below the point at which the

thermostat may be set to cut off the gas the pressure of the part 20 against the short arm of the thermostat lever 21 lifts the long end of the latter and with it the gas valve 27, thus allowing fuel to flow from the pipe G to the pipe I and thence to the main burners of the heater where it is ignited by the ordinary pilot light supplied independently with gas through the pipe 31. When the temperature of the flowing water rises above the point of thermostatic cut-off the expansion of the positive thermostat element 18 raises the part 20 sufficiently to allow the gas valve 27 to be seated under the pressure of its own spring 28, and thereby cut off the flow of fuel to the main burners of the heater. These successive opening and closing movements of the gas valve will be continued as the temperature of the flowing water falls below and rises above the predetermined point of cut-off as long as the parts are kept in the above described operative relationship to each other by the operation of the lever 14. But when the flow of water is stopped the pressure on the two sides of the water actuated member 7 is equalized, and the latter member is returned to its lower position both by the action of gravity, and by the action of the spring 16 on the lever 14. The downward movement of the arm 14 releases the thermostat lever 21 from engagement with the member 20, and the gas valve is closed—no matter what may be the temperature of the water in the heater at that time—both by the action of its own spring 28 and by the action of the spring 16 which, as already explained, then exerts pressure on the valve stem 26 through the engagement of the lever 14 with the adjustable collars 29. If, when the flow of water is stopped, the water actuated member 7 should from any cause be held in its upper position no damage can result from such sticking, since the control mechanism will still continue to act in such a case in the same manner as it does while the water is flowing. But such sticking of the water piston 7 in its elevated position can be overcome, if desired, by providing its central opening with a spring controlled check valve 32 which will prevent the backward flow of liquid from the heater coils to the liquid in the water main. Under such circumstances the heating of the inclosed liquid in the heater coils will exert a positive pressure on the upper side of the piston 7, and will thus force it back to its seat thereby permitting the lever 14 to fall and disengage the thermostat lever from operative engagement with the thermostat. If desired the upper end of the thermostat chamber 5 can be provided with a passage way 33 leading to the upper portion of the piston chamber 2, the piston chamber end of this passage way 33 being so located that it

will be opened when the piston 7' is in its lowest position, and closed as soon as the piston is raised. In this way a circulating port can be provided which will permit the water in the heater coils to circulate freely through the thermostat chamber 5 between the outlet 4 and the inlet 3 of the heater coils when no water is being discharged from the latter.

- 10 It will be observed that the operation of this mechanism involves the action of only two springs, to-wit, the gas valve spring 28 and the main spring 16, the latter serving not only to return the water actuated member to its initial position when the flow of liquid is stopped, but also serving to positively close the gas valve 27, if the gas valve spring 28 should fail to do so. It will also be observed that the mechanism is extremely 20 simple in its character and reliable in its operation, and is capable of adjustment so as to be made operative by any desired flow of water, however small, and also capable of being adjusted to shut off and turn on 25 the gas at any desired temperature.

In the construction shown in Fig. 4, 1' indicates the cold water supply pipe leading from the water main to the piston chamber 2', and 35 indicates the pipe leading from 30 this piston chamber to the inlet connection 3' which communicates with the upper end of the heater coils. 4' indicates the outlet from the lower end of these heater coils which communicates with the thermostat 35 chamber 5', and 6' indicates the pipe leading from the upper end of this thermostat chamber to the house supply system. The water actuated member 7' which is used in this construction is very similar in its general form to the piston member 7 which is used in Fig. 3, save that the central opening through this piston member is not closed by a plug, but is closed—when no water is flowing through the heater—by the engagement 40 of the end of the conical boss 36 with the outer or left-hand face of the piston member 7', by the pressure of the spring 37. The stem 11' of the water actuated member 7' carries at its outer end an adjustable 45 thumb nut 13' which engages with the upper end of a lever 39 which is pivoted at 15' on the frame of a control mechanism, and which is also pivoted at its lower end—at 38—to the upper end of the lever 21'. 50 The latter engages at its lower end with an adjustable thumb nut 25' on the gas valve stem 26'. The gas valve 27' is normally held against its seat by the spring 28' thus preventing any flow of fuel from the gas 55 supply pipe G to the gas delivery pipe I.

To the left of the lever 21' is a second lever 14' pivoted at 40 and provided with a set screw 41 bearing against the lever 21'. Springs 42 and 43 mounted upon rods 44 and 45 press the ends of the levers 14' and

39, respectively, to the left. The thermostat in the casing 5' is of the liquid type comprising a pair of tubes 46 connected at their upper ends and opening at their lower ends into a chamber 47 containing a suitable liquid. The chamber 47 communicates with the interior of the diaphragm 48 provided with a knife edge 49 bearing against the lever 14'.

When the outlet from the heater is opened the piston 7' is moved to the right causing the lower end of the lever 39 to move to the left. The swinging of the upper end of the lever 21' to the left causes the lower end to move to the right opening the valve 27'. When the water in the heater rises above a predetermined temperature the expansion of the liquid in the thermostat causes the knife edge 49 to move to the right, thus causing the movement of the set screw 41 to the left. This movement permits the lower end of the lever 21' to move to the left permitting the closing of the gas valve 27'.

Fig. 5 illustrates another modification of the invention wherein G is the gas admission pipe; 5² is the thermostat casing to which the water from the heater is supplied through the connection 4²; 18² and 19² are thermostatic parts corresponding to the parts 18 and 19 of Fig. 3; 1² is the cold water admission pipe; 7² is the water piston; and 3² is the connection leading to the upper coil of the heater.

The thermostatic element 19² has its end bearing against a set screw 50 carried by the lever 14² pivoted upon the fixed knife edge 52. The left-hand end of the lever is pressed upward by the spring 53 and carries a set screw 54.

The piston 7² is pushed downward by a spring 55 and carries a piston rod 56 having the bearing point 57 at its upper end in engagement with a set screw 58 mounted in the lever 21². To the left-hand end of the lever 21² is pivoted the gas valve stem 26².

When the outlet from the heater is opened the water piston 7² is moved up carrying the lever 21² into engagement with the lower end of the said screw 54 and the further movement of the piston causes the downward movement of the gas valve stem 26² and the gas valve carried thereby, thus permitting a flow of gas to the burners of the heater. If the temperature of the water rises above a predetermined point the expansion of the tube 18² permits the rod 19² to move down, the spring 53 at such time moving the left-hand end of the lever 14² and the set screw 54 carried thereby upward. This upward movement of the set screw 54 allows the lever 21² and the gas valve stem 26² to move up, thus closing the gas valve.

Fig. 6 illustrates still another modification wherein G is the gas admission pipe; 27³ is the gas valve yieldingly closed by the spring 130

28³; 1 is the gas delivery pipe; 1³ is the water pipe; 7³ is the water piston; 3³ is the water pipe leading to the upper coil of the heater; 5³ is the thermostat casing to which 5 the hot water of the heater is supplied from the connection 4³; and 18³ and 19³ are thermostatic elements, the lower end of the element 19³ being provided with the bearing point 20³. Fulcrumed at 59 is the lever 14³ 10 whose lower end is provided with a set screw 60. A tension spring 61 tends to swing the lever 14³ to the right. A second lever 62 is pivoted at 63 and is provided with a set screw 64. The lower end of the lever 62 is engaged by the tension spring 65. The piston rod 66 extends through the lever 62 and is provided with the adjusting screw 67. The gas valve 27³ is provided with a stem 26³ pivoted to the end of the lever 21³, the upper end of such 21³ lying 15 between the set screws 60 and 64.

When the outlet from the heater is opened the water piston 7³ moves to the left causing the upper end of the lever 62 and 25 the set screw 64 to move to the right. The set screw 64 engages the upper end of the lever 21³ carrying it against the set screw 60, after which the lower end of the lever 21³ is moved to the left opening the gas 30 valve 27³. When the water of the heater rises above a predetermined temperature the expansion of the element 18³ permits the element 19³ to move up the lower end of the lever 14³ moving to the right under the influence of the spring 61. This movement 35 permits the bearing end of the lever 21³ to move to the right, thus permitting the closure of the gas valve under the influence of the spring 28³.

40 What I claim is:

1. In combination in a water heater, a water container having an inlet and outlet, a gas burner, a conduit for supplying gas to the burner, a yieldingly closed gas valve in the conduit, a pressure operated member governed in its movements by changes of pressure induced by opening and closing the outlet from the container, a thermostatic element moved by changes in the temperature of the water, and lever means for opening the gas valve connected to the pressure operated member, the said lever means being out of contact with the thermostatic element when the outlet

from the container is closed, but brought into contact therewith by the movement of 55 the pressure operated member when the outlet from the container is opened, and the said thermostatic element being operative to control the position of the gas valve while 60 in contact with the lever means.

2. In combination in a water heater, a water container having an inlet and outlet, a gas burner, a conduit for supplying gas to the burner, a yieldingly closed gas valve in the conduit, a pressure operated member 65 governed in its movements by changes of pressure induced by opening and closing the outlet from the container, a thermostatic element moved by changes in the temperature of the water, and lever means for opening 70 the gas valve connected to the pressure operated member, the said lever means being out of operative engagement with the thermostatic element when the outlet from the container is closed, but brought into pivotal 75 contact therewith by the movement of the pressure operated member when the outlet from the container is opened, and the said thermostatic element being operative to control the position of the gas valve. 80

3. In combination in a water heater, a water container having an inlet and outlet, a gas burner, a conduit for supplying gas to the burner, a yieldingly closed gas valve in the conduit, a pressure operated member 85 governed in its movements by changes of pressure induced by opening and closing the outlet from the container, a thermostatic element moved by changes in the temperature of the water, a lever having a movable 90 fulcrum intermediate its ends and a connection for opening the valve on one side of such fulcrum, a pivot between the thermostatic element and the lever on the other side of such fulcrum but with the parts out 95 of contact when the outlet from the container is closed, and means operative from the pressure operated member when the outlet from the container is opened for moving the fulcrum of the lever so as to bring the 100 thermostatic element and lever into pivotal engagement, so that the gas valve is under the control of the thermostatic element while the said outlet is open.

FRANK L. O. WADSWORTH.
